UNITED STATES PATENT OFFICE

154,820

DESIGN FOR A WALKING TOY

Stanley Twarkowski, Detroit, Mich.

Application April 29, 1948, Serial No. 146,023

Term of patent 3½ years

(Cl. D34—15)

To all whom it may concern:

Be it known that I, Stanley Twarkowski, a citizen of the Republic of Poland and resident of the city of Detroit, county of Wayne, and State of Michigan, have invented a new, original, and ornamental Design for a Walking Toy, of which the following is a specification, reference being had to the accompanying drawings, forming part thereof, in which:

I claim:

The ornamental design for a walking toy, as shown.

STANLEY TWARKOWSKI.
